FLOATING TOOL HOLDER

Milton L. Benjamin and Stanley S. Benjamin, Cleveland, Ohio, assignors to Erickson Tool Company, a corporation of Ohio

Application March 26, 1954, Serial No. 418,976

5 Claims. (Cl. 279—16)

The present invention relates generally as indicated to a floating tool holder and more particularly to a floating tool holder of the general type disclosed in the Milton L. Benjamin et al. Patent No. 2,547,518, granted April 3, 1951.

In the aforesaid patent construction, and in the present construction as well, the full-floating holder compensates for both angular and parallel misalignment between the tool and the work spindles of machine tools, for example. In other words, in both constructions, there is a ball-type joint for universal angular adjustment of the tool supporting member, and interposed between such ball-type joint and the tool supporting member is, in effect, the elements of an Oldham coupling, the two elements of which are non-rotatably interfitted with each other, and respectively with the adjacent ball joint element, and with the adjacent tool supporting member to accommodate parallel misalignment along angularly related axes.

A principal object of this invention is to provide a floating holder which employs ball-joint trunnions which are disposed radially, rather than axially as in the case of the aforesaid patent.

Another object of this invention is to provide metallic resilient means for effecting pressure clamping to hold the parts of the assembly in adjusted position for self-aligning angular and transverse movement.

Another object of this invention is to provide a full-floating holder wherein the aforesaid resilient means are located in the holder according to whether or not the holder as a whole is rotary or non-rotary and also whether or not accurate control of depth of cut made in a work-piece is desired or necessary.

Other objects and advantages of the present invention will become apparent as the following description proceeds.

To the accomplishment of the foregoing and related ends, the invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a longitudinal cross-section view of one embodiment of the present invention, such cross-section having been taken substantially along the line 1—1, Fig. 2;

Fig. 2 is a transverse cross-section taken substantially along the line 2—2, Fig. 1; and

Fig. 3 is a fragmentary longitudinal cross-section view of a modified form of holder.

Referring now more particularly to the drawing and first to the form of the holder illustrated in Figs. 1 and 2, the same is shown as comprising a body or housing 1 which is provided with an elongated shank 2 adapted to be secured to the tool spindle of a metal working machine. Said housing 1 is further provided with an exteriorly threaded portion 3 within which is formed a conical seat

2. At diametrically opposite sides of said portion 3, adjacent said seat 4 and extending radially, are a pair of cylindrical pins 5 press-fitted or otherwise secured in place. As shown, said pins 5 extend radially inward to points adjacent the base of said conical seat 4. Within tubular portion 3 of said housing 1 is a series of three members 6, 7, and 8 respectively having a universally tiltable, driving connection with said housing 1 and transversely movable, driving connections with each other along angularly disposed paths.

The first of said series of members is a drive ring 6 which is formed with a spherical protuberance 9 adapted to make line contact engagement with the conical seat 4 and formed with a radially extending flange 10. Said flange 10 is formed with four equally spaced peripheral notches 11, two of which notches are adapted to fit rather closely over the inwardly projecting ends of said pins 5 for securing a positive driving engagement between housing 1 and ring 6, while allowing universal tilting of the latter while engaged with seat 4. The center line of said pins 5 preferably coincides with the center of the spherical protuberance 9. In this way, the notches 11 may reasonably closely embrace the ends of said pins 5 and yet said ring 6 may be universally tilted.

The second or intermediate one of said series of members is a ball-retainer ring 7 carrying a plurality of circularly arranged balls 14 therein, each of diameter greater than the thickness of said ring 7, the balls 14 being held in place in said ring 7 as by peening over of the edges of the openings in which the balls are fitted. As shown, said retainer ring 7 is formed with diametrically opposed axially extending lugs 15 which are adapted to fit, with some clearance, within the other pair of notches 11 in said drive ring 6 to secure positive driving of ring 7 through ring 6 and adjustment of said ring 7 along a path transverse to its axis, that is, in a direction parallel to the opposed lugs 15. Said ring 7 is further formed with another pair of similar diametrically opposed lugs 16 which extend axially in the opposite direction from and 90° out of phase with said lugs 15.

The third or last one of said series of members is a floating holder shank 8 of tubular form threaded at one end as shown and formed with a flange 17 at the other end, such flange having a pair of diametrically opposed notches 18 adapted to fit over said lugs 16 of said ball-retainer ring 7, whereby said holder shank 8 may also be adjusted transversely of its axis, but along a path at right angles to the path of transverse adjustment of said ball-retainer ring 7. The fit of the notches 18 over the lugs 16 provides a driving connection between said ball-retainer ring 7 and said holder shank 8.

It is to be understood that the holder shank 8 may be of any of the types shown in Figs. 1, 3, and 4 of the aforesaid Benjamin et al. Patent No. 2,547,518. The holder shank 8, as herein shown, is formed to accommodate a contractile collet, and for such purpose said shank 8 is provided with a bore having co-axial and axially spaced conical seats 19 and 20 comparable with the seats formed in the like shank member disclosed in the aforesaid patent and, as well, in the Milton L. Benjamin et al. Patent No. 2,358,300 dated September 19, 1944.

A contractile collet 21 is fitted into the bore of said shank member 8, said collet having conical faces 22 and 23 respectively engageable with the conical seats 19 and 20; and, as apparent, axial movement of said collet 21 into said holder shank 8 will effect contraction of said collet so as to grip a tool or the like therein. The collet 21 is moved endwise into the holder shank 8 as by means of the nose piece 24 which is threaded onto said shank 8 and bears on the outer end of said collet through the intermediary of a nose ring 25.

The series of members 6, 7, and 8 are clamped in the housing 1 by means of a counterbored ring 26 providing a shoulder which bears against the flange 17 of said holder shank 8, a clamp nut 27 being threaded onto said housing 1 and having an inturned flange 28 engaging the outer end of said ring 26. As shown, the bore through said ring 26 is slightly larger than the diameter of the holder shank 8 so that the latter may be angularly or eccentrically positioned therein.

Interposed between said drive ring 6 and housing 1 are a series of coil springs 29, and of course, instead of coil springs, a wavey spring washer or the like may be employed which bears against the flange 10 of said ring.

In the use of this form of the full floating holder, the shank of a reamer R or like tool is positioned within the collet 21 and the nose piece 24 is tightened to grip the tool.

The nut 27 is tightened to cause the spherical protuberance 9 to engage the seat 4 and then is backed off a slight amount, such as a quarter turn, and locked in such position as by means of the check nut 30. In this condition of the parts, there is a few thousandths inch clearance between the spherical protuberance 9 and its conical seat 4 whereby the tool R gripped by the collet 21 may readily align itself with the hole in the workpiece which is being reamed and thus may partake of angular and also parallel movement for such purpose.

However, because the spherical protuberance 9 and seat 4 are not in engagement at this time, this construction is not preferred in instances where accurate control of depth of the reamer R or other tool into the work is required. This holder is better employed in non-rotating use rather than rotating use, because initial angular misalignment might increase owing to rotation, whereupon difficulty would be encountered in the initial entry of the end of the tool R into the work. Of course, parallel misalignment is readily accommodated by the chamfer at the end of the tool R whether the holder is rotated or not.

The modified form of full-floating holder as illustrated in Fig. 3 is of substantially the same construction as that already described, and therefore repetition is not necessary. Instead of providing springs 29 between the housing 1 and the drive ring 6, the pressure ring 31 is of resilient construction and is here shown as made up of two telescoped rings 32 and 34 having a plurality of springs 35 therebetween, one ring 32 having a flange 36 engaged by the inturned flange of the nut 27, and the other ring 34 being counterbored to provide a shoulder which bears against the flange 17 of said holder shank 8. As before indicated, instead of a plurality of coil springs 35, a single spring may be employed or a wavey spring washer or the like.

Thus, when the nut 27 is tightened, the series of members 6, 7, and 8 are resiliently clamped together, the protuberance 9 being engaged with the conical seat 4 so that, even if this form of full-floating holder is employed in a rotating use, the angular misalignment is not increased owing to such rotation; and, therefore, the chamfered end of a tool R will readily enter a bore in the work as the holder is rotated and fed axially with respect to the work. During such feeding axially the tool follows the bore of the work by reason of the Oldham type coupling and the ball joint.

As a further feature of this invention, the springs 29 or 33, as the case may be, have slightly enlarged ends, thus necessitating threading of the same into place into

their sockets whereby they will not fall out upon disassembly of the holder.

Other modes of applying the principle of the invention may be employed, change being made as regards the details described, provided the features stated in any of the following claims, or the equivalent of such, be employed.

We therefore particularly point out and distinctly claim as our invention:

1. In a floating holder for tools and the like, the combination of a housing, a tool gripping assembly having a universally tilttable and transversely movable positive driving connection with said housing, said assembly comprising a plurality of adjacent members having such transversely movable positive driving connection with each other, one of said members and said housing having diametrically opposed, interfitting radial slots and coaxial, radial pins to provide such universally tilttable positive drive connection, and means for clamping said members together in said housing.

2. In a floating holder for tools and the like, the combination of a housing, a tool gripping assembly having a universally tilttable and transversely movable positive driving connection with said housing, said assembly comprising a plurality of adjacent members having such transversely movable positive driving connection with each other, one of said members and said housing having diametrically opposed, interfitting radial slots and coaxial, radial pins to provide such universally tilttable positive drive connection, and means for resiliently clamping said members together in said housing whereby a tool gripped by said assembly may shift to accommodate parallel and angular misalignment thereof with a workpiece.

3. The holder of claim 2 wherein said one member has a spherical end portion engaged in said housing and said means for resiliently clamping said members together in said housing acts through another of said members to urge said one member into engagement with said housing.

4. The holder of claim 2 wherein said means for resiliently clamping said members together includes a nut threadedly engaged with said housing to engage an adjacent one of said members, and resilient means between said one member and said housing resiliently permitting such universal tilting.

5. In a floating holder for tools and the like, the combination of a housing, a tool gripping assembly having a universally tilttable and transversely movable positive driving connection with said housing, said assembly comprising a plurality of adjacent members having such transversely movable positive driving connection with each other, one of said members and said housing having a pin and slot universal positive driving connection with each other, resilient means interposed between said one member and said housing to permit resilient universal tilting of said assembly with respect to said housing, and clamping means on said housing acting on another of said members so as to clamp said members together between said resilient means and said clamping means for relative transverse movement.
